UNITED STATES PATENT OFFICE.

LEWIS C. BAYLES AND FRED M. SLATER, OF EASTON, PENNSYLVANIA, ASSIGNEES TO INGERSOLL-RAND COMPANY, OF JERSEY CITY, NEW JERSEY, A CORPORATION OF NEW JERSEY.

LOCKING DEVICE FOR INDEPENDENT ROTATION MOTORS.

Application filed November 29, 1921. Serial No. 518,639.

To all whom it may concern:

Be it known that we, LEWIS C. BAYLES and FRED M. SLATER, citizens of the United States, residents of Easton, county of Northampton, and State of Pennsylvania, have invented a certain Locking Device for Independent Rotation Motors, of which the following is a specification, accompanied by drawings.

10 This invention relates to fluid actuated rock drills of the hammer type, having an independent motor for rotating the drill steel, but relates more particularly to a device for holding the motor against reverse 15 rotation when desired.

The objects of the invention are to enable the rotation motor to be cut out by mechanical means, and enable the machine to be slowly ratcheted on starting on a bad 20 surface and also to enable the operator to lock the gears of a gear drive and hold the motor against reverse rotation, when the drill steel sticks, so that he can ratchet the steel loose again, in which case the 25 motor will automatically pick up its rotation and continue to rotate the steel.

In a stope drill, for instance, having a fluid actuated rotation motor of the gear type for rotating the drill steel, the motor 30 is ordinarily mounted on the drill cylinder, or some portion of the machine connected to the drill cylinder, and in the type of machine to which this invention is applied 35 for purposes of illustration, the entire drill casing including the cylinder and rotation handle connected to the cylinder, tends to rotate in the opposite direction to the motor and the drill steel, or away from the operator, if the machine is drilling an up hole,

40 so that the operator must hold the handle. If the drill steel sticks, the handle would be pulled around, away from the operator, and in accordance with our invention, we have devised means for enabling the operator to 45 throw in the locking device by pulling the rotation handle towards him which rotates the drill cylinder in a direction opposite to the angular direction of the thrust of the motor on the drill cylinder. The operator 50 may then ratchet the machine back and forth until the drill steel is sufficiently loosened to enable the motor to automatically resume the rotation.

Further objects of the invention will here-

inafter appear, and to all of these ends the 55 invention consists of the features of construction and combinations of elements hereinafter fully described and claimed in this specification, and shown in one of its preferred forms in the accompanying drawings, 60 in which—

Figure 1 is a side elevation partly in longitudinal section of so much of the percussive and rotative elements of a stope 65 drill as will serve to illustrate the invention.

Figure 2 is a detail transverse sectional view of the machine partly broken away, taken on the line 2—2 of Figure 1, with the locking device in unlocked position,

Figure 3 is a view similar to Figure 2 70 with the locking device in locked position,

Figure 4 is a detail perspective view of the locking pawl, and

Figure 5 is a detail perspective view of the pawl spring. 75

Referring to the drawings, the machine comprises the cylinder A, having the front head B provided with the rotating chuck C into which the shank of the drill steel D extends in position to receive the blows of 80 impact of the fluid actuated reciprocating piston hammer E. Suitable ports and passages may be provided for the distribution of motive fluid for actuating the hammer, but these are not shown, as they form no 85 part of the present invention.

A motor casing F is mounted at the back end of the cylinder and closed by the back head G and a portion of an air feed cylinder H is shown connected to the back 90 head G. The parts of the casing so far described are held together by the usual side bolts J.

The fluid actuated rotation motor comprises the gears K and L in the motor casing F, the gear L being operatively connected by a train of gearing for rotating the drill steel. In this instance, a pinion O meshes with a gear P on the counter shaft Q which is provided with a pinion R meshing with the gear S on the chuck C. Motive fluid may be supplied to and exhausted from the rotation motor in any suitable manner (not shown).

In a rotation apparatus of the type described, the drill steel D will be rotated in the same direction as the motor gear L, to which the train of gearing is connected, and

in this instance, let it be assumed that the motor gear L is rotating counter-clockwise, as Figure 1 is viewed upward, in which case the drill steel D will also be rotated counter-clockwise as indicated by the arrow T on the gear S of the chuck C in Figure 2. The thrust of the rotation motor on the motor casing and drill cylinder will be in a direction opposite to the angular direction of the rotation of the driving gear L so that as Figure 1 is viewed, the rotation handle U connected to the motor casing and movable with the drill cylinder will be rotated clockwise or away from the operator, unless the handle U is held by the operator as is customary.

Unless some locking device is provided for the gear motor, the operator cannot ratchet his machine back and forth, by means of the handle U for any purposes, and in accordance with our invention, mechanical means for holding the motor against reverse rotation are provided, operatively controlled by the manipulation of the handle U. In this instance, a semi-circular pawl V, having a bevelled end W, is slidably mounted within the front head, around the pinion R, so that the bevelled end W may be moved into engagement with two of the teeth of the chuck gear S when desired. A convenient device for mounting the pawl consists of a rivet X having a head Y, which engages a slot Z in the end of the pawl opposite to the bevelled end W, and guides the said pawl. A leaf spring *a* having an aperture *b* through which the head Y of the rivet X passes, lies between the pawl V in the wall of the front head B and maintains the pawl in frictional contact with the teeth of the pinion R. The interior of the pawl V is preferably provided with serrations or shallow teeth *c* for producing greater frictional engagement between the teeth of the pinion R and the inside of the pawl than between the spring *a* and the wall of the front head in order that the pawl may be positively carried into engagement with the teeth of the gear S when the pinion R is rotated in the opposite direction to that indicated in Figure 2, or as indicated in Figure 3.

In the operation of the device, let it be assumed in the first place, that the operator desires to ratchet the machine on starting on a slanting surface for instance. By grasping the rotation handle U and pulling it towards him, as Figure 1 is viewed, and thus rotating the entire drill casing and the pinion R counterclockwise, the frictional engagement between the pinion R and the pawl V will carry the bevelled end W of the pawl into engagement with two teeth of the chuck gear S. By moving the handle back and forth the bevelled end W of the pawl will slide in one direction over the

teeth of the chuck gear S and then engage the teeth again in the other direction, so that the operator may ratchet his machine, until he desires to have motor rotation applied.

After the machine has been running, if the drill steel sticks, thus stopping the rotation of the chuck, the operator may pull the handle U towards him, throw the ratchet W to the position indicated in Figure 3, and then ratchet his machine until the steel is loosened sufficiently to permit the rotation to be resumed.

We claim:

1. In a fluid actuated rock drill of the hammer type, the combination with the cylinder and reciprocating piston, of an independent fluid actuated rotation motor for the drill steel, and mechanical means for holding the motor against reverse rotation connected to be operated by rotative movement of the drill cylinder opposite to the angular direction of thrust of the motor on the machine.

2. In a fluid actuated rock drill of the hammer type, the combination with the cylinder and reciprocating piston of an independent fluid actuated rotation motor for the drill steel, mounted on the drill cylinder, and mechanical means for holding the motor against reverse rotation connected to be operated by rotative movement of the drill cylinder opposite to the angular direction of thrust of the motor on the drill cylinder.

3. In a fluid actuated rock drill of the hammer type, the combination with the cylinder and reciprocating piston of an independent fluid actuated rotation motor for the drill steel, mounted on the drill cylinder, mechanical means for holding the motor against reverse rotation connected to be operated by rotative movement of the drill cylinder opposite to the angular direction of thrust of the motor on the drill cylinder, and a rotation handle connected to the drill cylinder capable of rotating the cylinder in said opposite direction to the angular thrust of the motor independently of the motor.

4. In a fluid actuated rock drill of the hammer type, the combination with the cylinder and reciprocating piston, of an independent fluid actuated rotation motor for the drill steel, mounted on the drill cylinder, and mechanical means for holding the motor against reverse rotation connected to be operated by rotative movement of the drill cylinder in the direction the motor tends to rotate the drill steel.

5. In a fluid actuated rock drill of the hammer type, the combination with the cylinder and reciprocating piston, of an independent fluid actuated rotation motor for the drill steel, mounted on the drill cylinder, mechanical means for holding the motor

against reverse rotation connected to be operated by rotative movement of the drill cylinder in the direction the motor tends to rotate the drill steel, and a rotation handle 5 connected to the drill cylinder capable of rotating the cylinder in said direction of rotation of the motor independently of the motor.

6. In a fluid actuated rock drill of the hammer type, the combination with the cylinder and reciprocating piston, of a rotating chuck, an independent fluid actuated rotation motor geared to said chuck, and a pawl adapted to engage one of said 15 gears for holding said gear against reverse rotation.

7. In a fluid actuated rock drill of the hammer type, the combination with the cylinder and reciprocating piston, of a 20 rotating chuck, an independent fluid actuated rotation motor geared to said chuck, and a pawl partially surrounding and carried on one of the gears adapted to engage another of said gears for preventing the reverse 25 rotation of said gears.

8. In a fluid actuated rock drill of the hammer type, the combination with the cylinder and reciprocating piston, of a rotating chuck, an independent fluid actuated rotation motor

30 mounted on the drill cylinder and geared to said chuck, and a pawl for preventing the reverse rotation of the chuck relative to the cylinder, said pawl being adapted to be thrown into engagement with one of said gears by rotative movement of the drill 35 cylinder opposite to the angular direction of thrust of the motor on the drill cylinder.

9. In a fluid actuated rock drill of the hammer type, the combination with the cylinder and reciprocating piston, of a 40 rotating chuck, an independent fluid actuated rotation motor mounted on the drill cylinder and geared to said chuck, and a pawl for preventing the reverse rotation of the chuck relative to the cylinder, said pawl being 45 adapted to be thrown into engagement with one of said gears by rotative movement of the drill cylinder opposite to the angular direction of thrust of the motor on the drill cylinder, and a rotation handle connected 50 to the drill cylinder for rotating the cylinder in said opposite direction to the angular thrust of the motor independently of the motor.

In testimony whereof we have signed this 55 specification.

LEWIS C. BAYLES.
FRED M. SLATER.
